OBJECT CONVEYING AND DISCHARGE DEVICE

George W. Whitehurst, Portsmouth, Va.

Application June 13, 1940, Serial No. 340,406

3 Claims. (Cl. 244—155)

This invention relates to a combined carrier and discharge device for a written message or other desired object or article.

The invention aims to provide, in a manner as hereinafter set forth, a device of the class referred to, for conducting an object to a distance above the earth and for automatically discharging it at a high altitude.

The invention further aims to provide, in a manner as hereinafter set forth, a device of the type referred to including a wind driven element for conveying an article to a high altitude and a bumper element engageable by said wind driven element as the latter travels upwardly to thereby provide for the actuation of said wind driven element for automatically releasing the object at a high altitude.

The device includes a stationary bumper element and a wind driven trolley element designed primarily, when the device is to be used, to be supported, by way of example, by the string of a kite, but it is to be understood that said element is to be installed with respect to any form of supporting means which is found applicable.

The invention further aims to provide, in a manner as hereinafter set forth, a device of the class referred to in the form of a toy, which provides when used in connection with a kite to add much to the pleasure of kite flying, promotes better kite making, calls for a longer and a better kite string, appeals to the young and old, amusing to children, capable of being readily used by children for sending messages between their homes or yards by raising one end of the kite string alternately to cause the trolley element to run back and forth, for sending a message to a distant point and for the discharging at an altitude of a prize to be recovered by one of a number of adults and children searching for it.

The invention further aims to provide, in a manner as hereinafter set forth, a device of the class referred to which is strong, durable, releasably secured upon a combined track forming and supporting means therefor, by way of example a kite string, affording considerable interest and amusement when used, capable of being employed for advertising purposes for dropping objects at high altitudes, readily installed with respect to its supporting means and inexpensive to manufacture.

Embodying the aims aforesaid and others which may hereinafter appear the invention consists of the novel construction, combination

and arrangement of parts as will be more specifically referred to and illustrated in the accompanying drawing wherein is shown an embodiment of the invention, but it is to be understood that changes, variations and modifications may be resorted to which fall within the scope of the claims hereinafter presented.

In the drawing:

Figure 1 is a side elevation of the device showing the same by way of example installed with respect to the string of a kite,

Figure 2 is a section on line 2—2 Figure 1 upon an enlarged scale,

Figure 3 is a top plan view of the trolley element of the device upon an enlarged scale, and

Figure 4 is an elevation looking to one side of the trolley element upon an enlarged scale when in released position.

With reference to Figure 1, the body of a kite is indicated at 5, the tail of the kite at 6 and the kite string 7.

The device includes a bumper element, generally indicated at 8, and a combined carrier and trolley element, generally indicated at 9, adapted to impact the element 8 for a purpose to be referred to.

The bumper element 8 may be formed of cork or rubber and preferably it will consist of a pair of oppositely disposed semi-circular sections 10, 11 of like form having their inner faces provided with lengthwise grooves which coact to provide an axial opening for the passage of the string 7. The element 8 is tightly secured to the string or track 7 by spaced wrappings 12 disposed circumferentially of element 8 and which fixedly secures the latter to string 7. It is to be understood, however, that element 8 may be formed of one piece of material having an axial opening for the passage of the string 7, and that such material will possess a compressible characteristic, such as cork or rubber to tightly bind against the string 7 when the wrappings 12 are fixedly placed in position about the abutment. The element 8 will be arranged on the upper portion of the string 7 and in the path of upward travel of the element 9.

The element 9 constitutes a means for traveling upwardly on the string 7 for carrying an object to a high altitude, and when element 9 impacts the bumper element 8 it will be actuated to an extent to release the object carried thereby, and such object will be delivered or discharged at a high altitude. The object conveyed by the element 9 is generally indicated at 13 and it will be of such form as to enable it to be

wind driven, and when attached to the trolley element 9 the latter will be carried upwardly on the string 7 until the element 9 impacts the bumper element 8. When impacting the bumper element 8, the element 9 will be actuated to an extent to release the object 13. When object 13 is released, the element 9 will travel downwardly by gravitation on the string 7, and when element 9 reaches the lower portion of the string 7 it will be grasped by the kite flyer or operator and another object releasably attached thereto.

The object 13 is illustrated by way of example in the form of a bag containing a prize or written message arranged therein. The mouth of the bag is closed by a string 15, which is so formed to provide an upwardly extending loop for the purpose of detachably connecting the object 13 to the element 9. It is to be understood that the object, which is to be conveyed to a high altitude by and then released from the element 9 may be of any character desired. The element is substantially of V-shape and formed of a pair of oppositely disposed extending spring control pivotally connected sections 17, 18 of like form but oppositely disposed. Each of the sections has its inner terminal portion in the form of a jaw 9 provided with outer and inner lengthwise edges. The outer edge has a straight upper or forward part 20 and an inwardly curved rear or inner part 21. The said inner edge consists of a straight forward or upper part 22 of less length than the edge part 20, an inwardly extending downwardly inclined intermediate part 23 and a rear or straight part 24 of less length than the edge part 22. The lower straight edge part 24 constitutes a gripper and the edge parts 22, 23 provide wall forming portions of an opening to be referred to. The jaw 9 merges at its forward or upper end into one side of the bottom edge of a disc-like member 25, which has a portion offset inwardly relative to said jaw. The member 25 is formed with an axial opening 26. Integral with the outer side of the top edge of the member 25 is an upstanding outwardly inclined suspension arm formed of outer, intermediate and inner portions 28, 29, 30 respectively merging into each other and disposed in offset relation. The inner portion 30 of the arm 27 is provided on its inner side with a lateral extension 31 having a straight edge part 32 which constitutes a stop for a purpose to be referred to. Integral with and extending outwardly from the upper terminal part of the portion 28 is a downwardly inclined support 33 merging at its outer end into a vertically disposed flat retainer 34 of yoke-shape form, which is disposed at right angles to the outer end of the support 33. The latter gradually increases in width from its point of emergence with the portion 25. The retainer which also constitutes an impactor is arranged below and is suspended in spaced relation with respect to the upper end of the arm 27. The portion 28 of the arm 27, in proximity to the upper end thereof is formed with an opening 35 in which is secured one end of a lateral extending shaft 36. Revolvably mounted on the shaft 36 and suitably connected thereon is a grooved pulley 37. The portion 30 of the arm 27 is provided with spaced aligned openings 38 forwardly of the extension 31 for a purpose to be referred to.

When element 9 is assembled, the members 25 are arranged in opposed relation and have their openings 26 align. The sections 17, 18 are pivot-

ally connected together by a pivot member 39 extending through the aligned openings 26.

One of the jaws 19 is offset to that member 25 with which it is integral to provide for the straight edge parts of the jaws to abut for a purpose to be referred to. The portion 30 of one of the arms 27 is offset relative to the member 25 with which it is integral, to provide for the straight edges 32 of the extensions to abut for a purpose to be referred to.

The retainers 34 carried by the supports 33 are oppositely disposed with respect to each other, but are arranged in spaced alignment when the arms 27 are disposed in extended relation with the straight edge parts 24 abutting or with said straight edge parts grasping an object 13.

The controlling spring for the sections 17, 18 is indicated at 40 and it is V-shaped contour. Each of the arms of the spring 40 is formed at its free end with a hook-like terminal portion 41. The said portions 41 coact with an opening 38 of the arms 27 for connecting the spring 40 to said arms, and the action of the spring is to normally maintain the element 9 in the portion as shown in Figure 1. The straight edges 32 of the extensions 31 limit the extent of the shifting of the arms towards each other when moving the jaws 19 away from each other to release the object 13, and when in released position element 9 will appear as shown by Figure 4.

The inner side edges of the jaws 19, when the sections 17 are extended coact to form a normally closed opening between the jaws 19 for the passage of the loop 16 when the edge parts abut, whereby the jaws 19 will suspend the object or article 13, as is shown by Figure 1. When the jaws 19 are open, the inner edge parts 23 thereof facilitate the passage of the loop 16 from between the jaws 19 on the release or discharge of the object 13 from the element 9. When the edge parts 24 grasp an object, immediately upon the opening of the jaws such object is discharged.

When the element 9 is arranged relative to the string or track 7, the pulleys travel on the latter and the string passes through the retainers 34. As the retainers are oppositely disposed, they function in connection with the pulleys to releasably hold the element 9 on the string 7. When element 9 is mounted on string 7 it will appear as shown by Figure 1.

The providing of each of the arms 27 with a plurality of openings 38 will permit of increasing or decreasing the tension of the spring 40 depending upon connecting the spring to the outer or to the inner opening 38 on each arm 27. When the spring is connected to the arms 27 it will be disposed at an inclination to the latter. The spring 40 normally tends to spread the arms 27 apart and also functions to maintain the pulleys travelling on the spring 7.

The form of element 9 is such that as it is being forced upwardly by the wind driven object, the string helps to open the jaws when element 9 impacts element 8.

The edge parts 24 of the jaws 19 will act as pinchers or grippers to hold flat wind driven objects and the opening 42 will be employed for the passage therethrough of a loop extended from other forms of wind driven objects; under such conditions the jaws will function to not only hold flat objects but also objects of different forms.

The device not only may be used as a toy, but also for commercial purposes, because it may

be employed for dropping circulars, cards, or tickets as is now done by an airplane.

The element 9 is reversible as either retainer 34 may be employed to impact element 8 to provide for the opening of the jaws to release the object carried. The retainers 34 form broad impacting surfaces.

To prevent the element 9 from crashing into the hand of the operator when it lowers by gravitation on the return just described about a fifteen inch circle with the hand that is holding the kite string, when the element 9 is about fifteen feet from the operator and under such conditions the element 9 will spin around on the string 7, come to a stop and strike the operator's hand lightly.

The jaws 19 are so disposed to let the loop connecting an object thereto twist out of the jaws, as the object suspended is being rapidly rotated by the wind, and under such conditions the element 9 will return by gravitation and it will not be required to pull the kite in to release an object.

The jaws are so formed and the element 9 so constructed whereby a heavy pull by the object will release the jaws relative to the object before the impact of element 9 is had with the abutment.

In operation there will be objects suspended that will have relatively small surface area for the wind to hit, there would be a slow travel up, and maybe a lull in the wind would cause the toy to stop at the bumper with no impact, but as soon as wind pressure increased, the pull would effect a release, the bumper acting as a fulcrum for the jaws to open by the pull of the object.

Until the toy reaches the bumper the power to pull out of the jaws is used to pull the toy up, this power is offset by the spring, but when the toy is against the bumper, the pulling power of the object is used to pull the jaws open and effect a release.

What I claim is:

1. A normally extended actuatable reversible combined carrier and trolley element for releasably suspending a wind driven object and adapted for travelling upwardly on an inclined track to impact an abutment disposed in the path of travel of and to actuate the element to release the object, said element comprising a pair of oppositely extended selectively shiftable sections pivotally connected together at a point between their horizontal medians and lower ends, each of said sections having an upper terminal portion offset with respect to its lower terminal portion, said upper terminal portion being provided at its upper end with a revolvably suspended trolley for travelling on the track, an outwardly directed downwardly inclined support on the side edge of said upper terminal portion and an upstanding retainer integral with and disposed at right angles to the outer end of the support for the passage of the track, said retainer being spaced from and disposed at right angles to the pulley and capable of impacting the abutment on the upward travel of said element, each of said sections having its lower terminal portion in the form of an adjustable jaw, a controlling spring common to and connected to said sections for normally maintaining said pulleys in projected relation with respect to each other, said jaws coacting for releasably suspending the wind driven object from

said element to cause said object to propel said element upwardly on the track to thereby provide for a retainer to impact the abutment to actuate one of the sections of said elements towards the other to release said object, and said retainers correlating with said pulleys for maintaining the latter on the track.

2. A normally extended actuatable reversible combined carrier and trolley element for releasably suspending a wind driven object and adapted for travelling upwardly on an inclined track to impact an abutment disposed in the path of travel of and to actuate the element to release the object, said element comprising a pair of oppositely extended selectively shiftable sections pivotally connected together at a point between their horizontal medians and lower ends, each of said sections having an upper terminal portion offset with respect to its lower terminal portion, said upper terminal portion being provided at its upper end with a revolvably suspended trolley for travelling on the track, an outwardly directed downwardly inclined support on the side edge of said upper terminal portion, and an upstanding retainer integral with and disposed at right angles to the outer end of the support for the passage of the track, said retainer being spaced from and disposed at right angles to the pulley and capable of impacting the abutment on the upward travel of said element, each of said sections having its lower terminal portion in the form of an adjustable jaw, a controlling spring common to and connected to said sections for normally maintaining said pulleys in projected relation with respect to each other, said jaws coacting for releasably suspending the wind driven object from said element to cause said object to propel said element upwardly on the track to thereby provide for a retainer to impact the abutment to actuate one of the sections of said elements towards the other to release said object, said retainers correlating with said pulleys for maintaining the latter on the track, said pulleys being arranged on inner faces of and extended above the upper ends of the said upper terminal portions, and said retainers extending inwardly from the outer ends of said supports.

3. A normally extended actuatable reversible combined carrier and trolley element for releasably suspending a wind driven object and adapted for travelling upwardly on an inclined track to impact an abutment disposed in the path of travel of and to actuate the element to release the object, said element comprising a pair of oppositely extended selectively shiftable sections pivotally connected together at a point between their horizontal medians and lower ends, each of said sections having an upper terminal portion offset with respect to its lower terminal portion, said upper terminal portion being provided at its upper end with a revolvably suspended trolley for travelling on the track, an outwardly directed downwardly inclined support on the side edge of said upper terminal portion and an upstanding retainer integral with and disposed at right angles to the outer end of the support for the passage of the track, said retainer being spaced from and disposed at right angles to the pulley and capable of impacting the abutment on the upward travel of said element, each of said sections having its lower terminal portion in the form of an adjustable jaw, a controlling spring common to and connected to said sections for normally maintaining said pulleys in projected relation with respect to each

other said jaws coacting for releasably suspending the wind driven object from said element to cause said object to propel said element upwardly on the track to thereby provide for a retainer to impact the abutment to actuate one of the sections of said elements towards the other to release said object, said retainer correlating with

said pulleys for maintaining the latter on the track, said supports gradually increasing in width outwardly, and said spring being of V-form having its base seated on one section and its legs engaging in both sections.

GEORGE W. WHITEHURST.
